J. L. RUSHTON

MOUNTING OF SPINDLES OF SELF ACTING MULES

Filed Oct. 30, 1924

INVENTOR:

James Lever Rushton,
BY: Francis E. Boyce

ATTORNEY.

UNITED STATES PATENT OFFICE.

JAMES LEVER RUSHTON, OF BOLTON, ENGLAND.

MOUNTING OF SPINDLES OF SELF-ACTING MULES.

Application filed October 30, 1924. Serial No. 746,718.

To all whom it may concern:

Be it known that I, JAMES LEVER RUSHTON, a subject of the King of Great Britain, residing at Kay Street Works, Bolton, in the county of Lancaster, England, have invented new and useful Improvements Relating to the Mounting of Spindles of Self-Acting Mules, of which the following is a specification.

10 The invention relates to improvements relating to the mounting of spindles of self-acting mules and has for its object to provide an improved mounting for the spindle bolster.

15 In the specification of British Letters Patent No. 161,769 granted to me was described and claimed a mounting for spindles consisting of two plates, one superposed and welded or otherwise secured upon the other

20 and both secured to the bolster bracket, the opposite edges of the plates being bent over and the front edge of the top plate which was the thinner of the two plates was cut or sheared true and the present invention constitutes an improvement or modification thereof.

According to the present improvement the double plate is dispensed with and a single plate substituted therefor the edges being 30 bent over at either side and one of said edges is extended downwardly for some distance in contact with a downward extension of the bolster bracket for example to a depth approximately equal to the width of the plate or thereabouts and at its extreme lower edge the plate is turned at right angles in order to give rigidity.

35 The spindle bearing or bolster is bolted or otherwise fixed to the deeper side of said plate by which means the construction is simplified while the rigidity of the bolster plate is retained or increased.

40 And in order that the said improvement may be more clearly understood and readily 45 carried into effect I will now proceed aided by the accompanying drawing more fully to describe the same.

The drawing illustrates an end elevation of part of a bolster bracket of a mule having the present improvement applied thereto.

50 Referring to the drawing, 1 represents the spindle, 2 represents the spindle bearing or bolster, and 3 represents the bolster bracket.

55 According to the present improvement a single plate 4 is employed, which plate is bent longitudinally thereof to form a pair of flanges 4^a and 4^b at right angles to the plate, one at each side of the bolster bracket 3, the flange 4^a being of greater width than the flange 4^b and bent at right angles adjacent to 60 its lower edge to form another flange 4^c, in order to give greater rigidity to the structure.

65 The bolster bracket 3 is provided with a downward extension 3^a, with which the flange 4^a of the plate 4 is maintained in contact and is securely fixed thereto by a screw 5^a, the spindle bearing or bolster 2 being in turn fixed by means of a screw 5 to said flange 4^a. This flange is provided for the 70 purpose of facilitating the alignment of the spindles whereby the construction of the spindle mounting is simplified while the rigidity of the bolster plate 4 is retained or increased.

75 What I claim as my invention and desire to secure by Letters Patent is:—

In a spinning mule, the combination of a spindle-bearing bracket having a downward extension, a plate secured to said bracket and bent longitudinally thereof to form a pair of flanges at right angles to the plate, one of said flanges being wider than the other and maintained in contact with the downward extension of said bracket, said wider flange 80 being bent near its outer edge to form another flange at right angles to said wider flange, and a spindle bearing mounted upon said wider flange and said downward extension.

85 In testimony whereof I have signed my name to this specification.

JAMES LEVER RUSHTON.
